(57) **CLAIM**

The ornamental design for a product dispenser, as shown and described.

DESCRIPTION

FIG. 1 is a top perspective view of a product dispenser showing our new design, shown in the sealed position;

FIG. 2 is a top perspective view thereof, shown in an open position;

FIG. 3 is a front elevation view of the product dispenser of FIG. 1;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front elevation view of the product dispenser of FIG. 2; and,

FIG. 10 is a left side elevation view thereof.

The broken lines in the drawings illustrate the portions of the design that form no part of the claim.
